(57) **CLAIM**

The ornamental design for a surface configuration of a front end for a vehicle, as shown and described.

DESCRIPTION

This application is related to the following co-pending applications, of the inventor, filed on even date herewith: Application Ser. No. 29/190,181, entitled "Surface Configuration of a Headlight for a Vehicle".

Application Ser. No. 29/190,180, entitled "Surface Configuration of a Radiator Grill for a Vehicle"; and

Application Ser. No. 29/190,182, entitled "Surface Configuration of a Radiator Grill for a Vehicle".

FIG. 1 is a front view of a surface configuration of a front end for a vehicle according to my novel design; and, FIG. 2 is a left, front perspective view of the surface configuration of a front end for a vehicle according to my novel design, the right, front perspective view being mirror symmetrical.

The broken lines are for illustrative purposes only and form no part of the claimed design.
